UNITED STATES PATENT OFFICE.

JOHN D. McDONALD, OF SUDBURY, ONTARIO, CANADA, ASSIGNOR TO McDONALD HYDRO-ELECTRO HEATING COMPANY LIMITED.

ELECTRICALLY-HEATED RADIATOR.

1,211,606.

Specification of Letters Patent.

Patented Jan. 9, 1917.

Application filed January 8, 1913, Serial No. 741,132. Renewed November 23, 1916. Serial No. 133,065.

To all whom it may concern:

Be it known that I, JOHN D. McDONALD, a citizen of the United States, residing at Sudbury, district of Sudbury, Province of Ontario, Canada, (and whose post-office address is Post-Office Box 64, Sudbury, Ontario, Canada,) have invented a certain new and useful Improvement in Electrically-Heated Radiators, of which the following 10 is a full, clear, and exact description.

The object of this invention is to provide a portable electrically heated radiator of simple construction, whereby a minimum amount of current is consumed for the 15 amount of heat or radiation required under a low temperature, and wherein the heating element of the electric heater will not show any heat-glow or color under varying temperatures, and may be controlled to vary 20 its heating effect.

The invention consists of a radiator comprising a series of independent thin sheet metal sections suitably connected and adapted to removably receive the heating unit and 25 to produce the most effective action of the heating unit upon the water contained in the radiator, all substantially as I will proceed now more particularly to explain and finally claim.

30 In the accompanying drawings illustrating the invention, in the several figures of which like parts are similarly designated, Figure 1 is a sectional view projected on a plane indicated by line 1—1, Fig. 3, and 35 passing longitudinally through the center of the radiator. Fig. 2 is a sectional view of a modified form of one of the sections of a specially-designed radiator providing an increasing water capacity toward the top of 40 the radiator. Fig. 3 is an end elevation of the radiator with a modified form of base and showing the spacer in dotted lines. Fig. 4 is an end elevation, on a larger scale, of the set nut for securing the expansion tank 45 in the radiator sections. Fig. 5 is a longitudinal section, on a larger scale, of the expansion tube detached. Fig. 6 is an end elevation, on a larger scale, of the heating unit, and Fig. 7 is a longitudinal section, 50 on a larger scale, of the heating unit.

The radiator comprises any suitable number of independent thin, flat, straight water sections K, each constructed of a pair of thin sheet metal plates with an interposed 55 spacer T, arranged longitudinally and cen-

trally of the plates, said spacers consisting of narrow strips of metal, and riveted or otherwise secured to the plates, and extending to within short distances from the upper and lower ends of the sections and forming water spaces upon opposite sides of the spacers and open water spaces above and below the spacers. The water sections K are mounted in any suitable manner on a base or support a which is preferably provided with ball casters b, Fig. 1, or on a base a' with roller casters b', Fig. 3, to permit easy removal of the radiator from one room to another, or from place to place, or its temporary shifting for sweeping and 60 cleaning purposes.

The upper edges of the radiator sections K are inclined inwardly from opposite sides toward the center, as shown in Fig. 3, to reduce the space in the upper ends of the 75 sections above the normal water level therein for a purpose presently appearing.

Arranged in suitable openings in the upper ends of the sections K and serving to connect and hold the sections in place is an 80 expansion tube F (see Fig. 5) having water ports N communicating with the water chambers in the sections K. The expansion tube F is securely fixed in said water sections by means of a cap O fitted in one end 85 of said tube and a set nut B engaging the other end thereof. Fitted in the cap O is an automatic relief valve G of usual construction, communicating with the expansion tube F. Arranged in suitable openings in the 90 lower ends of the radiator sections K is a tube A forming a casing for the heating unit to be described, the lower ends of the radiator sections forming a water chamber surrounding the tube A. The tube A is securely held in place by means of a cap Q fixed to one end of the tube and a set nut D fitted upon the other end of the tube.

C is an open lid or flanged collar also 95 screwed upon the tube A adjacent to the set nut D and serving to hold the heating nut, preferably an electric heater, in place and to receive a connecting plug to be referred to.

The preferred form of heater comprises 100 a frame or cylinder R, of porcelain or other non-conducting material, having the spaced annular insulating shoulders H for supporting the frame or cylinder within the tube A, and provided with numerous perforations or 105 air passages L which communicate with a 110

circular chamber or air passage U, bored longitudinally through the center of the frame or cylinder R. The chamber or passage U may have a lining e of copper or any other suitable metal, (as shown in Fig. 7), if desired, and the lining provided with perforations d to register with the lateral air passages L in the frame or cylinder R. Connecting conducting rods V are arranged in suitable slots, grooves, or openings E in the frame or cylinder R with their ends exposed at suitable openings in the end of the cylinder, and are adapted to be connected to the heating wire J coiled around the frame or cylinder R. Any number of connecting conducting rods V may be applied to the frame R, in accordance with the desired variation in the heating effect of the coil, but as herein shown, three of such rods are provided, whereby the heating effect of the coil may be varied to obtain a high, medium or low temperature or heating effect of the heating unit or coil.

As shown in Fig. 7, one of the rods V extends the entire length of the frame R, another extends about to the center or middle of said frame, and the third rod extends only a short distance from the end of the frame, and said rods are connected with the coil J at the points X, Y, Z, so as to produce three independent circuits, one of said circuits including one half of the coil, another of said circuits including the entire coil, and the other circuit including the other half of the coil.

A plug P having three contacts adapted to enter the openings in the end of the frame or cylinder R and engage the ends of conducting rods V, is connected with a suitable source of current supply, by means of an ordinary three-wire flexible conductor e having its individual wires at one end connected with the contacts of said plug, the other ends or terminals of said wires being connected with three contact points of an ordinary three point switch f, and said switch in turn connected with the source of supply g in such manner as to be capable of turning the current entirely off, or to direct the current through the entire coil J to produce a low temperature or heating effect; or to direct the current through one-half of the coil J only to produce a medium temperature or heating effect; or to divide the current and direct the full force thereof to each section or half of the coil J to produce a high temperature or heating effect. That is to say, by thus regulating the supply of current to the coil and properly proportioning the divisions of the coil, the heating effect thereof, when one-half of the coil is used, is double that of the heating effect when the current is directed through the entire coil, and when the current is split or divided and the full force enters separately

the two halves of the coil, the heating effect is twice that of medium and four times that of low. By thus regulating the supply of current to the various portions of the heating coil, it is possible to properly and economically control the consumption of electrical energy according to the temperature of the outside open air or weather conditions. The three point switch may be provided with suitable words or other characters to indicate the "off", "low", "medium" and "high" positions of the switch.

As shown in Fig. 3, the radiator sections have parallel edges, and as shown in Fig. 2, the sides of the sections may taper longitudinally; that is to say, the sides of the sections may be inclined inwardly from top to bottom, so as to provide greater water capacity at the top than at the bottom, thus maintaining a greater volume of water at the top where it reaches its highest temperature, and the least volume of water at the bottom where it surrounds the heating element and becomes heated more quickly thus causing a more rapid circulation, and consequently reducing to a minimum the condensation due to radiating surface at the point farthest from the heating zone.

The operation is as follows:—The necessary current for the required radiation is transmitted from the source of supply through the switch and plug P to the current conducting rods V and from rods V to heating coil J. The coil J surrounding the frame or cylinder R transmits its heat units to the tube A, and at the same time transmits a large portion of said heat units to the frame or cylinder R, which gives off these heat units through the chamber or passage U and air ports L to the tube A. The tube A in turn transmits said heat units to the water in the water sections K, the latter radiating the heat into the air space to be heated. The water in the sections K, as it becomes heated, expands into the expansion tube F, the air in the upper part of the radiator being forced out by such expansion through the automatic valve G. By inclining or beveling the upper ends of the radiator sections K, as herein described and as shown in Fig. 3, the air space surrounding the expansion tube F is reduced considerably and this reduces the quantity of air contained in the upper portion of the radiator to a minimum sufficient for the expansion of the water, and hence provides for the quick exhaustion of the cold air contained in the radiator and the consequent rapid heating of the radiator sections.

By the construction herein shown and described, the heating element may be removed from the radiator for renewal and repairs, and replaced without the removal of the tubes. The radiator sections are light and durable and hence the radiator as a whole

may be readily and easily moved from place to place; and furthermore, constructing the radiator of very thin sections permits the use of a minimum quantity of water to be heated, thus not only economizing heat but shortening the time necessary to start heat radiation, and provides a maximum radiating surface.

What I claim is:—

10 1. A radiator, comprising a series of independent thin, flat radiator sections, each constructed of a pair of thin flat sheet metal plates united at their edges and an independent narrow strip of metal centrally and longitudinally and vertically arranged between and terminating short of the upper and lower ends of said plates and riveted to the plates, said sections adapted to be partially filled with water, a heating unit applied to said radiator for heating the water therein, an expansion tube connecting the upper ends of said sections and communicating with the spaces therein above the water level, and an automatic valve for exhausting the air from said sections through said expansion tube.

20 2. A radiator, comprising a series of thin, flat independent sections, each constructed of a pair of thin flat sheet metal plates united at their edges, and an independent narrow strip of metal centrally and longitudinally and vertically arranged between said plates and terminating short of the upper and lower ends of the plates and riveted to the plates, and means for connecting said sections.

3. An electrically heated radiator, comprising a series of thin, flat, independent radiator sections adapted to be partially filled with water, means for connecting said sections, including a tube passing through the lower ends of said sections and adapted to receive an electric heating unit for heating the water in said sections, an expansion tube passing through the upper ends of said sections and communicating with the spaces above the water level therein, and an automatic valve fitted in said expansion tube, whereby the air is confined in the spaces at the upper ends of said sections and automatically exhausted therefrom as the water is heated by said heating unit.

4. A radiator, comprising a series of thin, flat straight sections, each constructed of a pair of plates, united at their edges, and an interposed spacer riveted together, the sides of each section inclined from end to end to provide greater water capacity at one end of the sections than at the other.

5. A radiator comprising a series of thin, flat, straight sections, each constructed of a pair of plates, united at their edges, and an interposed spacer riveted together, the sides of each section inclined inwardly from top to bottom, to thereby provide greater water capacity at the top of said sections than at the bottom thereof.

Corrections in Letters Patent No. 1,211,606.

It is hereby certified that in Letters Patent No. 1,211,606, granted January 9, 1917, upon the application of John D. McDonald, of Sudbury, Ontario, Canada, for an improvement in "Electrically-Heated Radiators," errors appear in the printed specification requiring correction as follows: In the grant the assignee was erroneously described and specified as "McDonald Hydro-Electric Heating Company Limited," whereas said assignee should have been described and specified as *McDonald Hydro-Electro Heating Company Limited*; page 1 of the printed specification, line 101, for the word "nut," second occurrence, read *unit*; and that the said Letters Patent should be read with these corrections therein that the same may conform to the record of the case in the Patent Office.

Signed and sealed this 30th day of January, A. D., 1917.
